UNITED STATES PATENT OFFICE.

THOMAS H. WARREN, OF DEXTER, IOWA.

AUTOHEMIC THERAPY POTENTIZER.

1,417,219.

Specification of Letters Patent. Patented May 23, 1922.

Application filed August 22, 1921. Serial No. 494,261.

To all whom it may concern:

Be it known that I, THOMAS H. WARREN, a citizen of the United States, and a resident of Dexter, in the county of Dallas and State 5 of Iowa, have invented a certain new and useful Autohemic Therapy Potentizer, of which the following is a specification.

The object of my invention is to provide an auto-hemic therapy potentizer or bottle 10 shaker of simple and efficient construction.

In preparing remedies for auto-hemic therapy treatments, it is the practice to take from the patient a certain amount of blood and at a proper time to mix the blood in solution with certain ingredients for thereafter 15 treating the patient with the complete solution. The solution is thoroughly shaken for mixing and it is desirable to have some simple device for thoroughly shaking and 20 agitating the bottles for mixing the solution.

It is my object to provide a simple device 25 for properly holding the bottles and holding the corks or closure members therein and for thoroughly shaking the bottles in a proper way for as long a time as may be desired.

With these and other objects in view, my invention consists in the construction, arrangement and combination of the various parts of my device, whereby the objects contemplated are attained, as hereinafter more 30 fully set forth, pointed out in my claims, and illustrated in the accompanying drawings, in which:

Figure 1 shows a vertical, sectional view 35 through a machine embodying my invention taken on the line 1—1 of Figure 5.

Figure 2 shows a detail, sectional view taken on the line 2—2 of Figure 1.

Figure 3 shows a detail, sectional view 40 illustrating the method of mounting the motor.

Figure 4 shows a detail, sectional view of a portion of the bottle holding device, the spring being omitted; and

Figure 5 shows a top or plan view of the 45 bottle holding device.

In the accompanying drawings, I have used the reference numeral 10 to indicate a cylindrical casing, in which part of the 50 mechanism of my machine is received. Mounted on the bottom of the casing 10 is a supporting bracket 11, in which is journaled a shaft 12. On the shaft 12 is a wheel or the like 13. Mounted on the side wall of 55 the casing 10 is a bracket 14 having vertically spaced parallel projecting members

15. The members 15 are tubular in form and have in their respective upper and lower adjacent faces, elongated slots 16.

I provide a motor 17, having at its upper 60 and lower portions upwardly and downwardly projecting members 18, terminating in horizontal, cylindrical members 19. The members 19 are slid into the tubular supports 15 against the tension of springs 20 65 received in the tubular members 15, as shown in Figures 1 and 3.

On the shaft 21 of the motor is a disc 22 arranged with its periphery in engagement with the periphery of the wheel 13. Fixed 70 on the shaft 12 is an eccentrically mounted disc 23. A pitman 24 is clamped on the disc 23 to permit said disc to rotate in the clamp members 25, which may be locked by means of a screw bolt 26 in proper position on the 75 disc 23.

The top 27 of the casing 10 is detachable and is fastened in position by means of screws or the like 28. Mounted in the top 27 is a cylindrical bearing or journal 29, having a flange 30, which may be secured to the top 27 by means of screws 31.

Slidably journaled in the bearing 29 is a shaft 32, which is pivoted at 33 at its lower end to the pitman 24. The upper end of the 85 shaft 32 is reduced in size at 34. Resting on the lower end of the reduced portion 34 of the shaft 32 is a washer 35. Mounted on the reduced portion 34 and resting on the washer 35 is a platform or disc 36. On the upper 90 end of the reduced portion 34 is screwed a nut 37, for rigidly fastening the disc 36 to the shaft 32. The disc 36 has in its upper surface a series of recesses 38 adapted to receive bottles 39. In the necks of the bottles 95 39 may be mounted the ground glass corks or other closure devices 40.

The recesses 38 are arranged preferably equi-distantly in a circle around the disc 36. Secured to the disc 36 and extending upwardly therefrom is a series of rods 41 arranged in a circle around the disc equi-distantly from each other and located between the respective recesses 38.

Slidably mounted on the upper ends of 105 the rods 41 is an annular ring 42. On the rods 41 above the ring 42 are screw nuts 43. Slidably mounted in the ring 42 above the respective recesses 38 are short rods or pivots 44, having on their upper ends, heads 45 110 and on their lower ends downwardly opening caps 46.

There is mounted on each rod or shaft 44 above its cap 46 and below the ring 42, a coil spring 47.

In the use of my improved machine, the 5 operator grasps one of the caps 46 and forces it upwardly toward the ring 42, thereby compressing the spring 47. A bottle may then be inserted in position with its lower end received in one of the recesses 38, and 10 thereupon the cap 46 may be lowered to fit over the cork or other closure device 40.

As many bottles may be placed in position as the disc 36 will hold. The tension of the 15 spring 47 may be regulated by means of the nuts 43, whereby the ring 42 may be forced downwardly.

It will be understood that in ordinary use, the parts are so adjusted that when the bottles are in position, the heads 45 will project above the ring 42, so that after the shaking operation has been performed, the operator may grasp the head 45, for raising the cap 46 against the spring pressure, for thereby readily releasing the bottle closure 25 40 from the cap and permitting the easy removal of the bottle.

After the bottles have been placed in position on the disc 36 and the caps 46 have been adjusted properly, the motor is started.

30 The frictional engagement of the disc 22 with the wheel 13 will impart rotation from the motor shaft to the wheel 13 and the shaft 12. The rotation of the shaft 12 and the eccentric disc 23 thereon will impart reciprocating motion to the pitman 24 and shaft 32 and to the disc 36 and the bottles 39 thereon.

The frictional engagement between the wheel 13 and disc 22 is yieldingly maintained by means of the springs 20.

40 It will be seen that where a machine of this kind is used, the shaking operation can

be accurately regulated. The speed of the motor being known and the degree of shaking being understood, accurate results can be attained by operating the machine for the 45 proper length of time.

My machine can be made at a low cost and is simple in construction and operation.

It is of a type not likely to get out of order and will thoroughly and efficiently 50 accomplish the desired agitation of the bottles and will give the bottles the proper shaking movement to thoroughly mix and commingle the contents thereof.

Some changes may be made in the construction and arrangement of the various parts of my improved machine without departing from the real spirit and purpose of my invention, and it is my intention to cover by my claims, any modified forms of structure, or use of mechanical equivalents, which may be reasonably included within their 55 scope.

I claim as my invention:

In a device of the class described, a support having a plurality of recesses therein for receiving the bottom end of bottles, a plurality of posts on said support, an annular member slidably mounted on said posts, means on said posts for limiting the upward 70 movement of the annular member, a plurality of rods slidably mounted in said annular member having heads on their upper ends and caps, formed with a downwardly, extending, peripheral flange on their lower 75 ends, springs on said rods between said caps and said annular member, whereby a closure member placed in the neck of a bottle may be engaged by said cap and yieldingly held in position for the purposes stated. 80

Des Moines, Iowa, August 16, 1921.

THOMAS H. WARREN.
